(57) **CLAIM**

The ornamental design for a cleaning device, as shown and described.

DESCRIPTION

FIG. 1 is a perspective view of a first embodiment of the new design for cleaning device;

FIG. 2 is a front view of the device of FIG. 1;

FIG. 3 is a back view of the device of FIG. 1;

FIG. 4 is a right side view of the device of FIG. 1;

FIG. 5 is a left side view of the device of FIG. 1;

FIG. 6 is a top view of the device of FIG. 1;

FIG. 7 is a bottom view of the device of FIG. 1;

FIG. 8 is a perspective view of a second embodiment of the new design for cleaning device;

FIG. 9 is a front view of the device of FIG. 8;

FIG. 10 is a back view of the device of FIG. 8;

FIG. 11 is a right side view of the device of FIG. 8;

FIG. 12 is a left side view of the device of FIG. 8;

FIG. 13 is a top view of the device of FIGS. 8; and,

FIG. 14 is a bottom view of the device of FIG. 8.

The broken lines in the drawings are shown for illustrative purposes only and form no part of the claimed design.

1 Claim, 14 Drawing Sheets
